UNITED STATES PATENT OFFICE.

RALPH C. SIMMONS, OF BEVERLY, MASSACHUSETTS, ASSIGNOR TO UNITED SHOE MACHINERY CORPORATION, OF PATERSON, NEW JERSEY, A CORPORATION OF NEW JERSEY.

HEEL-BUILDING MACHINE.

Original application filed October 24, 1918, Serial No. 259,578. Renewed December 2, 1920. Serial No. 427,847.

To all whom it may concern:

Be it known that I, RALPH C. SIMMONS, a citizen of the United States, residing at Beverly, in the county of Essex and State 5 of Massachusetts, have invented certain Improvements in Heel-Building Machines, of which the following description, in connection with the accompanying drawings, is a specification, like reference characters on the 10 drawings indicating like parts in the several figures.

This invention relates to heel building machines, and more particularly to that class 15 of machines adapted to form a heel, or part of a heel, from a series of lifts previously die-died out of leather, leatherboard or equivalent sheet material.

The various features of the invention are 20 herein shown and described as embodied in a machine which is completely automatic in its operation. It should be understood, however, that the utility of many of these 25 features is not restricted to a completely automatic machine but that they may advantageously be employed in other connections, in heel building machines which are only partially automatic in operation.

A principal object of the invention is 30 to produce a heel building machine which shall be capable of operation at a high speed with great certainty and accuracy and which shall produce heels of a uniformly high quality with a minimum of care and skill on the part of the operator.

35 With this end in view, one feature of the invention comprises an improved lift assembling mechanism, including a support upon which a row of heel lifts may be deposited, in combination with unidirectional 40 means operating in a single movement to collect the lifts in a heel pile in a suitable form or receiver. By the provision of a collecting device movable in one direction only a considerable advantage in speed and 45 ease of operation is gained over machines employing collecting devices of the reciprocating type wherein a substantial amount of time is lost in effecting the idle return stroke of the collector. This feature of the 50 invention may be embodied advantageously in an endless carrier or chain provided with series of spaced apart, depending lift engaging fingers movable along the lift support in proper time relation to the deposit

of series of lifts thereon, in combination 55 with means for moving the carrier intermittently through distances sufficient to produce complete heel piles.

Another feature of the invention resides 60 in the provision, in combination with mechanism for pasting and collecting a series of heel lifts into a pile, of means for producing a dry or unpasted lift and assembling it with those which are pasted, in such a manner as to avoid any application of paste 65 to that surface of the dry lift which is destined to become an outer face of the heel blank. As herein disclosed, this result is accomplished by producing and advancing the dry lift to the heel form in a path outside of the path of the pasted lifts, thus keeping it out of contact with those parts 70 of the machine which may have received paste from the pasted lifts. This lift thus is kept dry and clean until the first pasted lift is deposited upon it. Preferably, the dry lift is produced and advanced to the heel assembling form in a plane above the path in which the pasted lifts are advanced and is dropped into the form in advance of 75 the first pasted lift, which is deposited upon the dry lift, leaving the lower face of the latter clean and untouched by the adhesive.

80 A further feature of the invention relates to the provision of a heel lift assembling form, having improved means for causing its bottom member to descend gradually to deepen the lift receiving cavity as successive lifts are delivered to it, and subsequently to rise until it is flush with the top 85 of the form to permit the heel to be removed horizontally. In the illustrated construction this lowering of the bottom of the heel form is controlled by a cam timed to 90 co-operate with the lift collecting mechanism, which may advantageously be controlled by a cam upon the same cam shaft.

95 Still another feature of the invention has to do with the combination, with a heel form and a presser member for pressing heel lifts 100 together in the form, of a lift collecting device passing directly through the presser member. An important advantage of this arrangement is that it is not necessary to retract the lift collecting device to permit the 105 operation of the presser.

Other features of the invention, more or less specific, will become apparent in read-

ing the following detailed description, in connection with the accompanying drawings illustrating one embodiment of the invention, it being understood that variations 5 in the several features may be employed without departing from the spirit of the invention, the scope of which is defined in the appended claims.

The terms "heel," "heel blank" and "heel pile" are used interchangeably throughout the specification and claims to denote a pile of lifts assembled in proper relation to form either a complete heel or a multi-lift section or deck suitable for assembly with other lifts 15 to form a complete heel.

Referring now to the drawings:

Figure 1 is a front elevation of a machine embodying the invention;

Fig. 2 is a right-hand end elevation;

20 Fig. 3 is a view partly in elevation and partly in cross section illustrating the pressing, ejecting and nailing devices;

Fig. 4 is a detail of the means for rotating the nail driver turret;

25 Fig. 5 is a plan view of the left-hand end of the machine with portions broken away;

Fig. 6 is a front elevation view showing details of the means for pasting and guiding the lifts to the form; and

30 Fig. 7 is a cross section on approximately the line 7, 7 of Fig. 6.

The frame of the machine comprises a bed 10 supported by legs 12. The continuously running pulley 14, driven from any 35 suitable source of power, is arranged to be operatively connected, at will, to the mechanism of the machine by a clutch arm 16 operated by a foot treadle 18. This connection is effected by clutching the pulley to a 40 driving pinion 20 which meshes with a gear 22 rigidly mounted upon a cam shaft 24 which extends the entire length of the machine. To this cam shaft are secured the 45 cams which effect or control the operation of the lift producing pushers, the collecting chain, the driver turret, the ejector mechanism, the presser anvil and the nail drivers.

The supply of heel lifts, which may be of 50 graded sizes or all of the same size, is contained in a series of adjustable magazines 26, 28, and the individual lifts are produced one from the bottom of each magazine, simultaneously, by a series of push plates or 55 pushers 30 reciprocated by a sliding bar 32 which is actuated by mechanism to be described hereinafter.

In the forward movement of the pushers 30, a row or series of lifts is produced and deposited in dispersed relation upon a supporting surface 34 upon the bed 10. The lifts thus deposited are indicated at 36.

A carrier in the form of an endless chain 38 passes around an idle sprocket 40 at one 60 end of the machine and a driving sprocket 42 at the other end. The driving sprocket

42 is secured to a shaft 44 upon which is also mounted a pinion 46 meshing with a vertically reciprocable rack 48 and carrying a radial arm 50 provided at its outer end with a pawl 52 arranged to engage in a suitably formed notch in the interior of the sprocket wheel, as shown in Fig. 1. It will be apparent that movement of the rack 48 downwardly will, through the pinion 46, arm 50 and pawl 52, cause rotation of the sprocket 70 wheel in a clockwise direction, while upward movement of the rack will have no effect upon the sprocket, the pawl passing idly by the notch. An idle sprocket 54 is carried in the outer end of the arm 56 of a bell crank 75 lever, which is loosely pivoted on the shaft 44 and has a downwardly extending arm 58 provided with a slot 60 and arranged to be adjustably secured to the stationary bracket 62 by a bolt 64. The purpose of the idle 80 sprocket 54 is merely to support and keep 85 taut the collecting chain.

The lift collecting carrier or chain is provided with three series of depending, rearwardly inclined collecting fingers 66, each 90 equal in number to the number of magazines plus one and all except the one at the left (see Fig. 1) being spaced apart equally with the spacing of the magazines. The left-hand finger is spaced further from the remaining fingers and is placed in position to engage and remove the completed blank from the heel form immediately upon the beginning of the movement of the chain.

It will be understood from the preceding 95 description that the movement of the chain 38, which is effected by the driving sprocket 42, is always in the same direction, that is to say, the lower or operative section of the chain always moves toward the left, as viewed in Fig. 1. For the purpose of 100 effecting this movement, a cam 68 is provided upon the shaft 24. This cam is engaged by a cam roll 70 on an arm 72 which is loosely pivoted at its rear end upon a rock 105 shaft 74 and has, at its forward end, a toothed segment 76, meshing with a pinion 78 upon a short shaft 80. Also secured to the shaft 80 in fixed relation to the pinion 78 is a gear 82 arranged to mesh with teeth 110 84 cut in the front face of the rack 48 which is guided for vertical movement in the bracket 62 and the gear casing 86. In one revolution of the cam 68 the segment arm 72 is moved down and back, turning the 115 shaft 80 first in one direction and then the other. The consequent rotation of the gear 82 causes the rack 48 to be moved first 120 downwardly and then upwardly. The pinion 78 and the gear 82 are so proportioned 125 that the downward movement of the rack 48 produced is sufficient to turn the driving sprocket 42 through two complete revolutions and this in turn produces a movement of the collecting chain for one-third of its 130

length, that is to say, a distance equal to the extent of one of the series of collecting fingers. The position in which the chain stops is such that the fingers 66 occupy positions between adjacent magazines and the lifts produced from the magazines by the pushers are deposited upon the support 34 in dispersed relation between the respective collecting fingers, as is clearly apparent in Fig. 1.

The pusher actuating bar 32 is operated by a cam 88 upon the cam shaft 24. A cam roll 90 engaging the cam 88 is carried in the forward end of an arm 92 rigidly secured to the rock shaft 74. Two upwardly extending arms 96, 98, also rigidly secured to the rock shaft connect the latter to the pusher bar 32. One revolution of the cam 88 effects a complete oscillation of the rock shaft 74 and consequently a complete reciprocation, forward and back, of the pushers. This is timed so to occur as to deliver the series of lifts upon the support 34 at the time when the collecting chain 38 is stationary.

Parallel guide members 100, 102 are provided upon the support 34 for keeping the series of lifts deposited upon the support straight and in alinement. These guide members are secured to the support by bolt and slot connections 104, permitting relative adjustment of the guides toward or from each other to accommodate lifts of different sizes.

The bottom 106 of the left-hand magazine is located in a plane spaced somewhat above the support 34, and the corresponding pusher 108 is also located in a correspondingly higher plane than that of the pushers 30. The member 106 extends forwardly partially across the lift support 34, as shown at 110 and co-operates with a plate 112 supported in the same plane but spaced from it by a distance sufficient to permit the passage of the collecting fingers therebetween to receive the lift produced from the magazine 28. This is the so-called "dry," or unpasted lift of the heel. The guide members 100, 102 are built up higher adjacent to the supporting members 110, 112, to guide the dry lift upon its way to the heel form. The left-hand ends of the said supporting members are deflected downwardly, as shown most clearly at 114 in Fig. 6, leading to the top of the form recess or cavity.

The heel form comprises an abutment 116 alining the breast edges of the lifts and a series of radially adjustable form jaws 118 co-operating therewith. The bottom of the heel form consists principally of an ejector member 120, which is vertically movable within the jaws and is provided with passages 122, through which the heel building nails may be driven. The ejector 120 is reciprocated vertically by a cam 124 engaged

by a cam roll 126 upon a lever 128 loosely pivoted at its rear end upon the rock shaft 74. The center line of the cam 124 is indicated by long and short dots in Fig. 3. The forward end of the cam lever 128 is connected by a link 130 to a head 132 guided to slide vertically upon a member 134, depending from the table 136 which carries the form jaws. The head 132 carries the ejector 120 which partakes of the movements of said head. The ejector cam 124 is so designed and timed that it descends gradually to deepen the form cavity while the lifts are being delivered serially and piled up in the form.

The lower side of the ejector is recessed at 138 to fit down over either of the nail blocks 140 carried at the extremities of the arms of a turret 142 mounted upon a vertical shaft 144 to rotate in a horizontal plane. Beneath each nail block is a driver plate 146 carrying nail drivers 148. Each driver plate 146 is slotted, as shown at 150, to fit over the head 152 of a driver plunger 154, which is reciprocated vertically at proper times by a cam 156 upon the cam shaft 24. This cam is engaged by a cam roll 158 on a cam lever 160 pivoted loosely at its rear end upon the rock shaft 74 and connected by a link 162 to the driver plunger. The shaft 144 supports loosely a pinion 164, with which meshes a horizontally reciprocable rack 166 connected by a link 168 to a cam lever 170 pivoted at 172 to a stationary bracket 174. The cam lever 170 carries a cam roll 176 operated by a cam 178 upon the cam shaft 24. The hub 180 of the gear 164 is notched at opposite sides, as shown at 182, and a disk 184 pinned to the lower end of the shaft 144 carries a pawl 186 arranged to enter the notches. It will be apparent that when the cam 178 operates to move the rack 166 to the right, as viewed in Fig. 3, the gear 164 and its hub 180 will be rotated through half a revolution in the proper direction to rotate the turret shaft and turret through the same angle while the return stroke of the rack 166 will be idle, by reasons of the one-way pawl and ratchet connection between the hub 180 and the disk 184.

After the lifts have been assembled in the form, it is necessary to press them together, and, if it be desired to drive one or more heel building nails, to hold them under pressure while this is being done. This pressing is accomplished by a presser or anvil 190 mounted to reciprocate vertically in a suitable stationary guide 192. The anvil is connected to the forward end of a lever 194 which is pivoted at its rear end to a stationary bracket 196. A rod 198 is pivoted at 200 to the lever 194 and, at its lower end, is connected to a lever 201 having at its forward end a cam roll 202 which is arranged for engagement with a cam 204 on the cam

shaft 24. A stiff spring 206 surrounds the rod 198. The lower end of the spring bears upon a collar 208 secured to the rod, and its upper end bears against the under side of the table 136. As may be seen by reference to Fig. 3, the cam 204 is so shaped that in its rotation the anvil 190 will be gradually raised, compressing the spring 206, and then suddenly released, whereupon the expansion 10 of the spring will cause the anvil to be forced suddenly downward, striking the heel pile a sharp blow and forcing it firmly into the form. A slot 210 is provided in the anvil or presser member 190, and the collecting chain passes through this slot. 15

A paste roll 212 is mounted for rotation in a tank 214 subjacent to the path of the lifts along the support 34. An adjustable scraper 216 serves to regulate the amount 20 of paste carried upon the surface of the roll. Resilient fingers 218, pressed yieldingly by coiled springs 220 serve to press the lifts down upon the paste roll as they pass over the latter.

25 Supporting members 222, extending beyond the form and flush with its top, receive the ejected heel and guide it to a delivery position where it may be deposited in a suitable device for conveying the heels away 30 in orderly arrangement. Such a device is indicated at 224, see Fig. 1, and may consist of a conveyor such, for example, as that disclosed in the copending application of Thomas Lund, Serial No. 258,849 filed Oct. 19, 1918. This conveyor may advantageously conduct the heels directly to a heel compressor, and the use of the machine of the present invention is particularly advantageous in this combination, since the operation 35 of assembling or piling up the lifts in the form follows so nearly instantaneously upon the application of the paste that it becomes possible to use an exceedingly quick drying paste with no risk of its setting or losing its adhesive quality before the lifts are brought together. It is possible to compress freshly built heels immediately after they are assembled only when a paste of this type is used.

40 The operation of the machine is as follows: Assuming that the machine has been stopped in the position shown in Fig. 1, with a finished blank resting upon the ejector 120 and the ejector raised until it is flush 45 with the top of the heel form, and a series of lifts deposited upon the support 34 ready to be assembled, the machine is started. At this time the pushers are in the retracted position illustrated in Fig. 5. Immediately 50 upon starting the machine the chain carrying the collecting fingers 66 advances toward the left, as viewed in Fig. 1, through a distance equal to one-third of its length. The first finger engages the previously finished 55 blank, pushing it off the ejector 120, across

the support 222 and dropping it in the conveyor 224. The next finger engages the dry lift upon the supporting members 110, 112, advancing it along said members and dropping it upon the ejector, which by this time 60 has descended below the tops of the jaws 118 so that the lift is retained in the form and the lift engaging finger passes over it. The following lifts of the series are advanced by their respective collecting fingers successively over the paste roll 212 and deposited one on top of another in the form. During all this time, the ejector 120 is descending and has reached a position where it is flush 65 with the table 136 by the time all the lifts are deposited. When all the lifts have been deposited the collecting chain stops, and the anvil 190 descends sharply, pressing the lifts compactly together and holding them under pressure. Prior to the descent of the ejector, the nail driver turret will have reached the position shown in Fig. 3, and the ejector, descending to the position indicated in dotted lines, the nail block 140 will enter the 70 recess 138 maintaining the passages in the nail block in line with those in the ejector. The drivers are now actuated to drive the heel building nail or nails upwardly out of the nail block through the passages 122 into the heel, the nails being clinched upon the 75 anvil 190 if they are sufficiently long. During the nailing operation the pushers 30, 108, are advanced to produce a new series of lifts 80 and deposit them upon the support 34 between the fingers of the next series which have now arrived in receiving position. 85

90 After the nails are driven, the ejector and anvil rise simultaneously. the anvil, however, moves faster than the ejector and consequently when both have arrived at the 95 upper limit of their movement the anvil is separated from the heel, as shown in Fig. 1, permitting the heel to be discharged. Immediately after the ejector 120 has risen sufficiently to permit the nail block 140 to 100 become disengaged from it, the driver plunger 154 being at the same time retracted, the turret 142 is rotated through half a revolution to remove the now emptied nail 105 block and bring into operative position the other nail block and drivers to which nails have been supplied by any suitable mechanism while it was in the left-hand position, 110 shown in Fig. 3. The parts are all now in the same position as when the machine was 115 started, and the operation may be repeated indefinitely as long as the supply of lifts is maintained in the magazines, a complete heel 120 pile or blank being produced at each cycle of such operation.

125 Having thus described my invention, what I claim as new and desire to secure by Letters Patent of the United States is:—

1. In a heel building machine, the combination of a series of lift magazines, a sup- 130

port adjacent to the magazines, means for removing a series of lifts from the magazines and depositing them upon the support in spaced relation, means for receiving a heel pile and means movable in one direction only for advancing said series of lifts along the support in spaced relation and delivering them one upon another to said receiving means.

10 2. In a heel building machine, the combination of a series of lift magazines, a support adjacent to the magazines, means for removing from the magazines lifts sufficient for a heel and depositing them upon the support in a series parallel to the magazines, a heel form below the plane of the support, and means movable in one direction only for advancing the series of lifts along the support and dropping them one upon another in said form to form a heel pile.

15 3. In a heel building machine, the combination of means for supporting a series of heel lifts in dispersed relation, and lift collecting means located above the supporting means and comprising a series of depending lift engaging fingers constructed and arranged for movement in one direction only.

20 4. In a heel building machine, the combination of means for supporting a series of heel lifts in dispersed relation, an endless chain above the supporting means, a series of lift engaging fingers depending from the chain, lift receiving means adjacent to the support, and means for moving the chain to advance the lifts along the support and deposit them in a pile on the lift receiving means.

25 5. In a heel building machine, the combination of means for supporting a series of heel lifts in dispersed relation, an endless chain located above the supporting means, a series of lift engaging fingers depending from the chain, lift receiving means adjacent to the support, and means for imparting intermittent movement to the chain to advance the lifts simultaneously along the support and deposit them in a pile on the lift receiving means.

30 6. In a heel building machine, the combination of means for supporting a series of heel lifts in dispersed relation, an endless chain located above the lift supporting means, a series of lift engaging fingers depending from the chain, and means advancing the chain step by step through distances greater than the separation of adjacent fingers, to advance the lifts simultaneously through corresponding distances.

35 7. In a heel building machine, the combination of means for supporting a series of heel lifts in dispersed relation, an endless chain located above the supporting means, a plurality of series of lift engaging fingers depending from the chain, and means for advancing the chain step by step through

distances equal to the space covered by one of said series of fingers.

40 8. In a heel building machine, the combination of a lift receiving form, means for pressing a heel pile in the form, and lift collecting means constructed and arranged to deliver a series of lifts to the form, a portion of said lift collecting means being located permanently immediately above the form.

45 9. In a heel building machine, the combination of a lift receiving form, means for pressing a heel pile in the form, and lift collecting mechanism occupying a permanent position over the form, constructed and arranged to deliver a series of lifts to the form.

50 10. In a heel building machine, the combination of a lift receiving form, means for pressing a heel pile in the form, a lift collecting device comprising an endless carrier, a portion of which is at all times immediately over the form, and means for actuating the carrier to deliver a series of lifts to the form.

55 11. In a heel building machine, the combination of a lift receiving form, a lift collecting device comprising a carrier constructed and arranged to deliver a series of lifts to the form, and a presser arranged to press a heel pile into the form, said presser being provided with a recess for the reception of a portion of the carrier, whereby a portion of the carrier may, at all times, be in position over the form.

60 12. In a heel building machine, the combination of a lift receiving form, a lift collecting device comprising an endless chain constructed and arranged to deliver a series of lifts to the form, and a presser arranged to press a heel pile in the form, said presser being recessed to permit the passage of the collecting chain therethrough.

65 13. In a heel building machine, the combination of means for supporting a series of heel lifts in dispersed relation, an endless chain located adjacent to the lift supporting means, a series of lift engaging fingers carried by the chain, and means for advancing the chain step by step through distances greater than the separation of adjacent fingers, to advance the lifts simultaneously through corresponding distances.

70 14. In a heel building machine, the combination of means for supporting a series of heel lifts in dispersed relation, an endless chain located adjacent to the lift supporting means, a series of lift engaging fingers, carried by the chain, equal in number to the number of lifts in the heel to be built, and means for advancing the chain by a single movement through a distance equal to the space covered by said series of fingers.

75 15. In a heel building machine, the combination of a lift receiving form, means for producing a series of lifts in a single plane, means for pasting the lifts of said series,

- means for producing a single dry lift in another plane, and means for assembling all of the lifts in the form to form a heel pile with a face of the dry lift outermost.
- 5 16. In a heel building machine, the combination of a lift receiving form, means for producing a series of lifts in a single plane, means for pasting the lifts of said series, means for producing a single dry lift in another plane, and means for delivering to the form first the dry lift and then the series of pasted lifts to form a complete heel pile with a dry outer face.
- 10 17. In a heel building machine, the combination of a lift receiving form, means for producing a series of lifts in a single plane, means for pasting the lower faces of the lifts of said series, means for producing a single dry lift in another plane, and means for delivering to the form first the dry lift and then the pasted lifts to produce a heel pile having dry outer faces.
- 15 18. In a heel building machine, the combination of a lift receiving form, means for producing a series of lifts in a single plane, means for pasting the lower faces of the lifts of said series, means for guiding the series of lifts to the heel form, means for producing and guiding a single dry lift to the form outside the path of the pasted lifts, and means for advancing all the lifts along their respective paths and depositing them in proper sequence in the form.
- 20 19. In a heel building machine, the combination of a lift receiving form, means for delivering a predetermined number of lifts serially to the form, a movable bottom member for the form, and positive means for lowering and raising the bottom member timed relatively to the lift delivering means to lower said bottom member continuously while the lifts are being delivered and then to raise said bottom member until it is flush with the top of the form.
- 25 20. In a heel building machine, the combination of a lift receiving form having a movable bottom member, means for delivering a predetermined number of lifts serially to the form, means for pressing the lifts in the form, and means timed to co-operate with the lift delivering and pressing means for lowering said bottom member progressively during the delivery of the lifts, maintaining it stationary during the pressing of the lifts, and then raising it until it is flush with the top of the form.
- 30 21. In a heel building machine, the combination of a lift receiving form having a movable bottom member, means for delivering a predetermined number of lifts serially to the form, positive means timed to co-operate with the lift delivering means for lowering said bottom member continuously during the delivery of the lifts to produce a heel pile and then raising it until it is flush with the top of the form, and means for removing the heel pile horizontally.
- 35 22. In a heel building machine, the combination of a heel form having a movable bottom member, a presser member constructed and arranged to press a heel pile into the form, and means for first lowering the bottom member and then the presser member and thereafter simultaneously raising both of said members.
- 40 23. In a heel building machine, the combination of a heel form having a movable bottom member, a movable presser member, means for advancing the presser member into engagement with a heel pile in the form to apply pressure thereto, and means for raising the bottom member to eject the heel pile from the form and simultaneously retracting the presser member faster and through a greater distance, to release the heel pile.
- 45 24. In a heel building machine, the combination of automatic means for repeatedly assembling series of lifts in the form of heel piles, means for securing the lifts together, means for conducting away the successive piles in orderly arrangement and automatic means for delivering the piles from the securing means to the conducting means.
- 50 25. In a machine of the class described, the combination, of a row of magazines, an endless chain collecting device movable in a path parallel to the row of magazines, a series of spaced apart blank engaging fingers on the collecting device, and means for moving the collecting device step by step through distances equal at least to the length of the row of magazines.
- 55 26. A heel building machine having, in combination, a movable receiving device, and means for serially feeding the lifts and delivering them in superposed relation to the receiving device and for progressively lowering said device as each lift is delivered thereto.
- 60 27. In a heel building machine, the combination of a lift receiving form, means for delivering a series of lifts successively to the form, a compressible bottom member in the form, and cam means for lowering the bottom member to deepen the form continuously as the lifts are delivered to it.
- 65 28. A heel building machine having, in combination, a plurality of lift magazines, means for producing therefrom a series of lifts in a row, means for operating upon the lifts, and an endless conveyor provided with means for engaging the lifts in said row and advancing them in succession to said operating means.
- 70 29. In testimony whereof I have signed my name to this specification.
- 75 RALPH C. SIMMONS.
